UNITED STATES PATENT OFFICE.

IRA S. BUNKER, OF NORTH SPRINGFIELD, MISSOURI.

COMBINED FIRE AND BURGLAR ALARM.

SPECIFICATION forming part of Letters Patent No. 357,366, dated February 8, 1887.

Application filed January 14, 1886. Serial No. 188,617. (No model.)

To all whom it may concern:

Be it known that I, IRA S. BUNKER, a citizen of the United States, residing at North Springfield, in the county of Greene and State 5 of Missouri, have invented certain new and useful Improvements in Combined Fire and Burglar Alarms; and I do hereby declare the following to be a full, clear, and exact description of the invention, such as will enable others skilled in the art to which it appertains to make and use the same.

My invention relates to improvements in fire and burglar alarms, the object of which is to provide a cheap, simple, reliable, and convenient device for giving an alarm in case of fire or burglary in any part of a house or other place desired to be protected. These objects I attain by means of the device illustrated in the accompanying drawings, forming a part of 15 this specification, in which—

Figure 1 is a plan view of the box with the cover raised to show the interior of the same. Fig. 2 is a detail of the alarm machinery. Fig. 3 is a detail, enlarged, of the attachment for a 20 door.

Similar letters of reference indicate corresponding parts in the several figures.

A represents a box or case, of any desired size and shape, which may be ornamented as desired. Said box has a suitable cover, B, hinged to one side, for convenience in opening the same. It also has a partition, C, which has one or more holes, c, and in one end, D, of the said box are also made one or more holes, d², 30 corresponding in number with the holes c, for receiving rods E. Said rods are of any desired size and length, and are provided with suitable springs, preferably spiral springs, F, as shown, which rest against the inside of the end D, and a pin or shoulder, e, on the lower or inner end of the rods E. The inner ends of rods E are notched at e² crosswise, so as to catch the cord G, and not slip off from it when they are permitted to go in to press upon it 40 for setting off the alarm. To the other ends of rods E are attached cords H, which extend to any or all parts of a building desired. Preferably a separate cord H is used for each room, passing around flues in garrets, over doors, or where fire is most likely to originate or burglars to enter. To the outer or farther

end of said cord is secured a suitable spring or weight to keep the spring F on the rods E drawn up against the end piece, D, and for holding rods E up so as not to engage cord G, 55 unless in case of fire or the opening of a door which is desired to be protected, when one of the cords H will be severed by burning off, or be cut off by the device, hereinafter explained, for setting off the alarm.

The device for giving the alarm for burglary consists of a button, I, secured to a door or window, having a hook, i², on one end to engage cord H, so that in case the door or window is opened it will pull on the cord, which is placed 65 through eyelets h, which are placed near the button, and are provided with a sharp or cutting edge, h², so that when the button is made to pull on the cord the cord will be severed and permit the alarm to ring.

The direction of the fire or disturbance may be known by examining the box A, which is placed in an office, or near the head of a bed, as desired, and the several cords or rods are numbered or designated, so as to tell from 75 where the cord is cut or the room or place to which each cord goes.

The alarm is constructed as any ordinary alarm. The one shown has a winding-shaft, J, on which is placed a coil-spring, K, with a 80 cog-wheel, L, having a pawl, l, and spring l² to keep it in place in the ratchet-wheel M, and a shaft, O, provided with a pinion, o², to engage the cog-wheel L, and a toothed wheel, o³, in which operates the escapement P. To the 85 escapement-shaft P² is secured the hammer-rod Q and arm R for preventing the alarm from sounding when it is held back.

S is any ordinary alarm-bell, secured in a suitable position onto the cover for being 90 struck by the hammer.

T is a lever, of any desired shape, and size pivoted in the box near the alarming machinery, one end having an arm, t, to rest against arm R, when the lever is in the position shown, to prevent the sounding. For this purpose a suitable spring, W, preferably a spiral spring, is secured to the inside of the box and to the other end of the lever T to hold it in place.

G is a cord, also secured to the same end of the lever T. It is placed around a pulley or

suitable support, *g*, and is attached firmly to the side of the box *g*². Thus when one of the cords *H* is cut or burned off the rod *E*, to which it is connected, is permitted to pass down, as shown at *E*², by means of the springs *F*, which draw upon the lever *T*, as indicated by the dotted lines, which releases the alarm and rings the bell. Thus I have a device that is certain in its action, as a slight pressure on the cord *G* will permit the alarm to ring.

In passing the cords *H* through ceilings and partitions small thimbles or tubes *Z* may be used, through which to pass the cord to protect it from mice, insects, &c., and for this purpose it may be tarred or otherwise prepared for preserving it, when desired, and in making connections with other buildings wire may be used in the place of the cords. For making connections with other rooms, windows, out-buildings, or any desired point, connection may be made with the main cord by means of a block, *X*. Said block has a hole through which the cord *H* is passed, or a notch in which it may be placed, as shown.

*E*³ is a rod extending through a hole in the block in a cross direction from the line of the main cord, and is provided with a knife or piece, *X*², having a sharp edge, which is placed in a slot, *X*³, so that it is free to move back and forth.

*F*² is a spring placed on the said rod and resting against the shoulder in the block *X*, and a pin on the back end of the rod for throwing the rod back.

*H*² is a cord secured to the end of the rod *E*³, and having a weight on its farther end to keep the knife drawn back. Thus it will be seen that should the cord *H*² be severed, from any cause, the spring *E*² will quickly draw down

the rod *E*³, and cause the knife *X*² to sever the 40 cord *H*, thereby sounding an alarm.

Having thus described my invention, what I claim as new, and desire to secure by Letters Patent, is—

1. The combination, with a suitable case, of 45 an audible alarm mechanism, as described, a spring-actuated lever connected with said mechanism by a rod, *t*, a cord, *G*, arranged beneath one or more spring-actuated rods, *E*, and connected to the lever *T*, and one or more 50 cords, *H*, leading off to a door or other object, and provided with a tension-weight, substantially as described.

2. The combination, with an audible alarm mechanism, the spring-actuated lever *T*, the 55 rod *t*, and rope *G*, having engagement with arm *R*, connected to lever *T*, of one or more spring-actuated rods, *E*, one or more ropes, *H*, passed over pulleys and provided with a tension-weight for connecting these rods with a 60 door-flue or other object, a slotted guide-back, a cutter, *X*², applied to a vertically-movable spring-actuated rod, and a cord passed over pulleys and provided with a weight, all substantially as described.

3. The combination, with an audible alarm mechanism constructed as described, and one or more spring-actuated rods, *E*, held up by a cord, *H*, and weight, of a door loosely connected by an eye to said cord, and one or more 70 devices adapted to cut said cord should the door be opened, substantially as described.

In testimony whereof I affix my signature in presence of two witnesses.

IRA S. BUNKER.
